HANDBAG

David E. Kadison, New York, N. Y.

Application September 5, 1951, Serial No. 16,519

Term of patent 3½ years

(Cl. D87—3)

To all whom it may concern:

Be it known that I, David E. Kadison, a citizen of the United States, residing at New York, in the county of New York and State of New York, have invented a new, original, and ornamental Design for a Handbag, of which the following is a specification, reference being had to the accompanying drawing, forming part thereof.

In the drawing

Fig. 1 is a top plan view of a handbag showing my new design,

Fig. 2 is a side view thereof; and Fig. 3 is a perspective view thereof.

I claim:

The ornamental design for a handbag, substantially as shown.

DAVID E. KADISON.
